Specification for Design.

Patented Feb. 10, 1920.

Application filed June 5, 1919. Serial No. 302,077. Term of patent 14 years.

To all whom it may concern:

Be it known that I, GEORGE B. SCOTT, a citizen of the United States, residing in Philadelphia, Pennsylvania, have invented a new, original, and ornamental Design for a Box, of which the following is a specification, reference being had to the accompanying drawings, forming part thereof, in which—

Figure 1, is a perspective view of a box showing the new and ornamental design forming the subject of my invention;

Fig. 2, is an end elevation of the box;
Fig. 3, is a side elevation thereof;
Fig. 4, is a vertical section on the line IV—IV, Fig. 3, and
Fig. 5, is a plan view.

I claim:

The ornamental design for a box, substantially as shown in the accompanying drawings.

GEO. B. SCOTT.
